(57) **CLAIM**

The ornamental design for a display screen with graphical user interface, substantially as shown and described.

DESCRIPTION

FIG. 1 is a front view of a display screen including a graphical user interface with a long access port icon in accordance with the present design;

FIG. 2 is a front view of a display screen including a graphical user interface with a standard access port icon in accordance with the present design;

FIG. 3 is an enlarged view of the long access port icon of FIG. 1 in accordance with the present design; and,

FIG. 4 is an enlarged view of the standard access port icon of FIG. 2 in accordance with the present design.

The broken lines in the drawings depict portions of the display screen and the graphical user interface are for illustrative purposes only and form no part of the claimed design.

1 Claim, 3 Drawing Sheets
